FUEL OIL BURNER

Leonard A. Pepp, Saugus, Mass., assignor to Lynn Products Co., Lynn, Mass., a corporation of Massachusetts

Application September 11, 1931, Serial No. 562,276

1 Claim. (Cl. 158—89)

This invention relates to fuel oil burners, more particularly to such oil burners for use in the fire pot of domestic ranges that may have been originally designed for burning coal. This kind of oil burner is shown in many prior patents, an example being Johnson and Leach No. 1,764,794, June 17, 1930.

In the design of these range oil burners the goal is to effect complete combustion so that a hot blue flame will be produced continuously. This may be true in a particular burner so long as the rate of oil supply is proportionate to the amount of air that is available for intermixture with the vapor. If the rate of oil supply is increased without increasing the air the combustion will be incomplete, the flame showing yellow where it emerges from the combustion chambers of the burner.

The object of this invention is to effect complete combustion of the oil, at whatever rate supplied within reasonable limits, and thus to distribute a maximum of heat throughout the fire pot of the range.

Accordingly a feature of the invention comprises an auxiliary air chamber or combustion cone designed to deliver to the flame, as it leaves the combustion chambers, the required amount of air to effect complete combustion of any excess gases which, because unconsumed, cause the flame to burn yellow with loss of heat.

To the accomplishment of this object and such others as may hereinafter appear, as will readily be understood by those skilled in the art, the invention comprises the features and combinations of parts which will first be described in detail and then particularly pointed out in their true scope in the appended claim.

The preferred form of the invention, applied for illustrative purposes to an oil burner of the said Johnson and Leach type, is disclosed in the accompanying drawings, in which:

Figure 1 is a central, vertical sectional view through one of two twin burners the bases of which are joined by a connecting web;

Fig. 2 is a view, in horizontal section, taken on the line 2—2 of Fig. 1;

Fig. 3 is a view, in plan, of the auxiliary air chamber; and

Fig. 4 is a view, in plan, of the cover of the burner on which the auxiliary air chamber is supported.

In the embodiment of the invention illustrated in the drawings the general design of the twin oil burner is similar to that disclosed in the Johnson and Leach Patent No. 1,764,794. A descrip-

tion of one of the twin burners will suffice for both, the connecting central bar 1 and side webs 2 being partially shown on Fig. 2. The central bar is apertured to receive a standard for supporting the oil burner within the fire box of the range.

The burner base comprises a circular casting 8 providing two concentric inner and outer vapor grooves 13 and 14 underlying inner and outer combustion chambers 15 and 16, and a central vaporizing chamber 20 in the form of a cup which is connected to the inner vapor groove 13 by a plurality of tubular radial ribs constituting conduits 10 for supplying vapor to the combustion chamber 15. The outer vapor groove 14 is connected to the inner groove by radial ribs 12 and certain of these ribs are tubular to form conduits for supplying vapor to the outer combustion chamber 16. The purpose and advantage of this mode of delivering vapor is described and claimed in my co-pending application Ser. No. 432,616, filed March 3, 1930. Oil is fed to the bottom of the cup 20 by a supply pipe 21, is there vaporized and passes therefrom to the two grooves 13 and 14. The combustion chamber 15 is formed by a pair of perforated sleeves 17 seated on shoulders on the walls of the groove 13 and the combustion chamber 16 is formed by a pair of larger sleeves similarly applied to the groove 14. The vaporizing chamber 20 is within a central air chamber 23 formed by the inner of the pair of sleeves 17, and is provided with a cover 24 seated loosely on the rim of the cup and centralized thereon by a plurality of wings engaging said inner sleeve 17. The cover 24 is removable for cleaning the vaporizing chamber when necessary. The segmental spaces 9 about the cup 20 and between the ribs 10 are open to supply air to the central heating chamber 23 and thence through the inner sleeve 17 to the combustion chamber 15. The segmental spaces 11 between the ribs 12 and between the two grooves also are open to supply air through the sleeves for combustion.

The inner three of the four sleeves support a removable top cover (Figs. 1 and 4) which may conveniently be a metal stamping having an outer flange 26 resting on the inner of the two outer sleeves 18, an adjacent depressed annular groove 27 for spacing said sleeve 18 from the adjacent sleeve 17 and a central depressed portion 28 engaging the inner of the two sleeves 17. The metal between the depressed portions 27 and 28 is cut away in the form of curved slots 29 through which pass the products of combustion from the inner

combustion chamber 15. The flange 26 is made narrow to leave the outer combustion chamber 16 open at its top.

The oil-burning and heat-developing capacity 5 of a burner of the kind above described may be greatly increased by providing an auxiliary air chamber disposed above the central air chamber and comprising a perforated wall through which the hot air from the central chamber 10 passes and by which the same is broken up, deflected to any unconsumed gases exhausted from the combustion chambers and mixed with the same. This current of air by mixing with any unconsumed or partially-consumed gases 15 from the combustion chambers effects the complete combustion thereof constantly to deliver a hot blue flame. This improvement increases the capacity of the burner about 33½%.

The invention contemplates the use of an 20 auxiliary air chamber which in its preferred form has an open bottom, a closed top and an upwardly and outwardly-flaring perforated wall. The exact shape of this auxiliary air chamber is rather immaterial and it may be of any other configuration 25 that provides a perforated wall disposed in proximity to the inner combustion chamber in such relation that the streams of air passing through the perforations thereof will intersect the flame arising from said combustion 30 chambers and any streams of partially-consumed gases therein.

The auxiliary air chamber (Fig. 1) through 35 which the object of this invention is attained may conveniently be seated on the central portion 28 of the top cover, and this central portion is provided with an aperture 30 permitting air from the central chamber 23 to pass into the auxiliary air chamber. The auxiliary air chamber, as shown, has a closed top or cover 31 and 40 a perforated wall 32 open at its bottom. The wall 32 is shown, in the present instance, in the form of an inverted truncated cone the smaller base of which rests in the depressed central portion of the cover of the burner and surrounds 45 the central aperture 30 thereof. The larger base flares outwardly above the combustion chambers and is provided at its upper edge with a plurality of out-turned lugs 33 which are secured, as by spot welding, to the under face of 50 the closed cover 31. In order to provide for as little escape of air as possible at the joint between the wall and its cover the lugs 33 may be formed by a plurality of pairs of inward slittings 55 through the upper edge of the wall (three or four lugs have been found to be sufficient in practice) and the metal therebetween is bent outward leaving a circular rim 35 extending thereabove. The cover 31, which may be a metal 60 stamping, is formed with an annular groove 37 at its under face and the upper rim 35 of the auxiliary air chamber wall is seated in this groove and is so dimensioned as to be forced tightly against the outer vertical wall thereof (see Fig. 1).

65

70

75

Air from the central chamber enters the auxiliary air chamber through the aperture 30 and passes out through the wall 32 in the form of minute streams which will cut across and commingle with any unconsumed or partially-consumed gases exhausting from the combustion chambers which renders combustion complete. Preferably the cover 31 is so dimensioned as to provide a rim flange 39 extending outward of the wall 32 to such an extent as to overhang the outer combustion chamber 16, thus to assist in confining the air streaming outward to a position for thorough mixture with the rising gases and preventing a dissipation thereof before admixture as desired.

In the use of oil burners of the general type generally in use having a solid cover over the central air chamber, an excessive rate of oil supply will not only produce a yellow flame indicative of incomplete combustion but the flame will tend to draw into conical form above the cover instead of spreading from the combustion chambers. With the improvement of this invention an increased supply of oil is completely consumed with a blue flame augmenting the developed heat about one-third and a flame of maximum diameter is maintained above the combustion chambers.

Asbestos wicks (see Figs. 1 and 2) in the vapor grooves may be used for priming or initially heating the burner until sufficient vaporization is induced in the chamber 20. The interior of the auxiliary air chamber may be inspected at any time by lifting it from the top cover on which it rests. This top cover and the vaporizing chamber cover are both removable for inspection and cleaning.

While the drawings show a burner base having circular vapor grooves with cylindrical perforated sleeves and a circular vaporizing cup, and auxiliary air chamber, because this form lends itself to cheapness of manufacture, it is within the scope of the invention to use other geometrical forms for some or all of the parts of the burner; nor is the novel auxiliary air chamber limited to use with an oil burner of the specific construction illustrated because it may be used with advantage on oil burners of other types.

The nature and scope of the invention having been indicated and its preferred embodiment having been specifically described, what is claimed as new, is:—

In a fuel oil burner, the combination with inner and outer concentric combustion chambers each formed by a pair of spaced perforated walls, the inner wall of the inner combustion chamber forming a central air chamber, and an auxiliary air chamber above and connecting with said central air chamber, said auxiliary air chamber having an upwardly and outwardly-flaring perforated wall overlying the top of the inner combustion chamber, an open bottom and a closed top providing a rim flange extending laterally above the outer combustion chamber.
